AIR LIFT PUMP

Joseph P. Ruth, Denver, Colo.

Application December 3, 1953, Serial No. 396,049

11 Claims. (Cl. 23—284)

As a development from and an improvement over the disclosures of my application for Letters Patent of the United States, Serial No. 287,141, filed May 10, 1952, this invention relates to internal combustion engine exhaust gas conditioners of the type characterized by an air lift pump for the agitation and circulation of a water charge in reaction to and to effective wetting relation with the inflow of exhaust gas to the conditioner, and has as an object to provide a novel and improved such air lift pump efficiently operative in association with such conditioners.

A further object of the invention is to provide a novel and improved construction and operative association of elements constituting an air lift pump in and for exhaust gas conditioners.

A further object of the invention is to provide a novel and improved air lift pump operative in association with an exhaust gas conditioner to facilitate and to enhance dispersion of exhaust gas infeed throughout and in intimate contact with a water charge.

A further object of the invention is to provide an air lift pump for an exhaust gas conditioner that is susceptible of limited adjustment and variation of its operative characteristics.

A further object of the invention is to provide a novel and improved air lift pump for an exhaust gas conditioner that is susceptible of adjustment to vary the proportions of gas and water fed therethrough.

A further object of the invention is to provide a novel and improved air lift pump in an exhaust gas conditioner that is characterized by flow paths and flow velocities conducive to thorough and intimate commingling of gas and water separately fed thereto.

A further object of the invention is to provide a novel and improved air lift pump for an exhaust gas conditioner that is simple and inexpensive of construction, adapted for use in and with conditioner units of diverse structural particularity, that is positive and efficient in attainment of the ends for which designed, and which is adapted for production to meet an infinite range of particular operating requirements.

With the foregoing and other objects in view, my invention consists in the construction, arrangement, and operative combination of elements as hereinafter set forth, pointed out in my claims, and illustrated by the accompanying drawings, in which—

Figure 1 is an isometric view, partially in section to show otherwise concealed construction, of an exhaust gas conditioner of the type shown in my earlier application as modified to give effect to the principles of the present invention.

Figure 2 is a side elevation, on an enlarged scale and partially in section to show otherwise concealed construction, of the air lift pump shown in view 1, portions of the view being broken away to conserve space.

Figure 3 is a side elevation of the improved air lift pump similar to and on a plane at right angles to the showing of Figure 2.

Figure 4 is a cross section taken on the indicated line 4—4 of Figure 2.

Figure 5 is a fragmentary, detailed elevation of the lower end of the air lift pump shown in the preceding views and as modified within the contemplation of the invention.

As an environment for the novelties and improvements hereinafter elaborated, an exhaust gas conditioner unit of the type disclosed in my earlier application is represented as including a housing adapted to confine a charge of water and defined by end walls 10, side walls 11, a bottom 12, and a removable and replaceable top 13. Baffles 14 depend from the top 13 in spaced parallelism with upper portions of the end walls 10 and in closing relation with and between the side walls 11 to terminate in free margins well above the bottom 12, and a reticulate or foraminous sheet 15 transversely of the housing in spaced parallelism with and above the bottom 12 supports an intersticed charge of diffusing material 16, which may be either inert or reactive to characteristics of the flow developed therethrough, in a depth above the said sheet sufficient to rise at each side of and above the free lower margins of the baffles 14 a distance less than will fill the upper portion of the housing. Outflow 25 from the housing is had from the upper portions of the housing end chambers defined by the baffles 14 through nipples 17 connecting through the top 13 and with a common flow line 18 which may expediently discharge through a diffusing member 19 of venturi type. A tubular conduit 20 closes at its lower end against the bottom 12 and upstands centrally within the housing and through the charge 16 to terminate in an open upper end above said charge and spacedly below the top 13, and an exhaust gas flow line 21 arranged to carry the exhaust gas 30 output of an internal combustion engine connects through suitable fittings with the upper end of a gas input line 22 intersecting the top 13 and depending interiorly of the housing within and in coaxial relation with the conduit 20 to terminate in an open lower end adjacent the base 35 of the conduit and spaced upwardly from the bottom 12.

With the typical organization shown and above described, the housing is charged with water to a level below the free lower margins of the baffles 14 and provision is made for access of the water charge to the interior of the conduit base, so that, as exhaust gas is introduced under the influence of its normal pressure through the lines 21 and 22 interiorly and adjacent the base of the conduit 20, uprise of the gas in the space between the conduit and the line 22 generates a pumping action effective to circulate water and admixed gas upwardly through and outwardly from the upper end of said conduit over and for percolation through the intersticed charge 16; the wetted gases being washed through the upper portion of said charge to ultimate escape past the free lower margins of the baffles 14 and away from the housing through the nipples 17, line 18, and element 19, and the drip from the charge 16 is returned to the water body for repetitious recirculation.

All of the foregoing is in accord with my previous disclosures and is herein represented only to typify the structural locus and operative environment wherewith the improvements herein below discussed are employable with practical advantage and to effect enhanced efficiency consequent upon a more thorough dispersion and wetting of the gas input and a more complete and intimate mixture 60 of the gas input with the water circulated through the conduit 20 deriving from the constructions and relationships detailed in the other views of the drawings as hereinafter described.

Giving effect to the principles of the present invention, 65 the conduit 20 is formed as a right cylindrical, tubular member open at such end and of appropriate length and

said conduit is based in end adjustably supported centrally of the housing by a ring or collar 23 which is disposed centrally of and with its axis perpendicular to the bottom 12 and permanently affixed and sealed to said bottom, as by means of welding. The upper portion of the 5 ring or collar 23 is interiorly threaded for coaction with external threads on the lower end of the conduit 20, thus to mount said conduit to upstand centrally of the housing and through the charge 16 with provision for adjustment in the spacing between the upper end of 10 said conduit and the housing top 13 consequent upon rotation of the conduit in its threaded engagement with the ring or collar. The input line 22 is also formed as a right cylindrical, tubular member sized to telescope within the conduit 20 and to define an annular channel of appropriate capacity between its exterior surface and the inner wall of the conduit. The line 22 is open at each end and is exteriorly threaded, as at 24, adjacent its upper end, so that when the threads 24 are engaged with and to mount the line 22 through a fitting 25 carried by the housing top 13 rotation of said line relative to said fitting effects adjustment of the line altitudinally of the conduit 20 to determine the spacing of the lower end of the line 22 upwardly from the housing bottom 12. The altitudinal dispositions of the conduit 20 and the line 22 are adjusted as may be desired and the top 13 is then secured in position to close the housing, whereafter the exterior end of the line 22 is coupled, by means of any appropriate fittings, to and as a flow extension of the line 21.

Water from the charge within the housing about the base of the conduit 20 and about the ring or collar 23 is admitted to the interior of the conduit through a pair of like, diametrically-disposed, gate openings 26 intersecting the conduit walls above the ring or collar 23 and at some distance above the lower end of the line 22, said gate openings 26 preferably being of isosceles trapezoid form arranged with their lesser parallel margins lowermost and flush with preferably integral tongues 27 extended inwardly and radially of the conduit to abut the adjacent wall of the line 22. To facilitate assembly of the pump and to maintain the lower end of the line 22 centered within the base of the conduit 20, short ribs 28 are fixed interiorly and adjacent the lower end of the conduit to project radially and inwardly thereof in a uniform spacing between the tongues 27 for engagement against the exterior of the line 22, upper corners of said ribs 28 being beveled or inclined, as shown, to guide the line 22 into seated relation therewith.

The elements of the improved pump are assembled and adjusted to dispose the lower end of the line 22 slightly below the lower end of the conduit 20 and to open for delivery of gas flow well above the housing bottom 12 and well below the plane of the tongues 27. Naturally, when there is no inflow of gas through the line 22, water from the housing charge will collect in the base of the conduit 20 and rise in the space between said conduit and the line 22 to the level of the housing charge. Initial inflow of the gas through the line 22 promptly clears water from the base of the conduit 20 and uprises between the conduit and line 22 with a pumping action which discharges the intermixed water and gas from the upper end of the conduit, and continued inflow of gas encounters water entering the conduit through the gate openings 26 in a metered amount determined by the area of said openings. The water entering the conduit is diverted by the tongues 27 and spread circumferentially of the line 22 at each side of each tongue and into the path of gas uprising past the tongue margins in divergent streams which tend to spiral oppositely and circumferentially of the line 22. As a consequence of the water diversion and gas stream divergence occasioned by the tongues 27, a very thorough dispersion of the gas in the form of fine bubbles is had throughout the volume of water entering the mixing passage, and the circumferential oscillation

of the mixture flow resulting from the gas stream divergence effects a very thorough admixture of the gas and water such as insures complete wetting of the gas and consequent dissolving of the soluble gas constituents in the entrained water.

While it is generally practical to proportion the size of the gate openings 26 for appropriate admission of water in proper relation to the gas input of a given conditioner unit, the construction shown and described is convenient of adaptation for adjustment in the effective size of said gate openings in the manner indicated by Figure 5. A sleeve 29 may be telescoped over and fitted for rotation about the conduit 20 above the ring or collar 23 and in position to close over the gate openings 26, and said sleeve 29 may be apertured, as at 30, to expose the full areas of the gate openings 26 when said sleeve is in one position of rotation relative to the conduit, a set screw 31, or equivalent securing member, being provided to fix the sleeve 29 to and in any desired angular adjustment about the conduit. In the arrangement shown, the sleeve 29 is available to reduce the effective open areas of the gates through which the water enters the conduit and to thereby determine the input of water in a desired proportioned relation to the infeed of the gas.

Since changes, variations, and modifications in the form, construction, and arrangement of the elements shown and described may be had without departing from the spirit of my invention, I wish to be understood as being limited solely by the scope of the appended claims, rather than by any details of the illustrative showing and foregoing description.

I claim as my invention:

1. In an exhaust gas conditioner having a housing adapted to contain water and an intersticed charge of diffusing material transversely of the housing above the water therein, a pump for the circulation of the housing-confined water through said charge in reaction to the input of exhaust gases to the housing, said pump comprising a conduit upstanding interiorly of the housing through said charge, a closed lower end on said conduit submerged in the housing-confined water, an open upper end on said conduit above said charge, means coaxial with and interiorly of said conduit defining an annular channel between its outer wall and the inner wall of the conduit, the lower end of said means being spaced above the closed lower end of the conduit, means for the input of exhaust gases through said first means to the lower end of the conduit for uprise through said annular channel, gate openings intersecting the conduit upwardly adjacent the lower end of said annular channel for the admission of water thereto, and a tongue radially and inwardly of the conduit at the lower end of each said gate opening in obstructing relation with said channel.

2. In an exhaust gas conditioner having a housing adapted to contain water and an intersticed charge of diffusing material transversely of the housing above the water therein, a conduit upstanding interiorly of the housing through said charge, a closed lower end on said conduit submerged in the housing-confined water, an open upper end on said conduit above said charge, means coaxial with and interiorly of said conduit defining an annular channel between its outer wall and the inner wall of the conduit, the lower end of said means being spaced above the closed lower end of the conduit, means for the input of exhaust gases through said first means to the lower end of the conduit for uprise through said annular channel, gate openings intersecting the conduit upwardly adjacent the lower end of said annular channel, and a tongue at and coextensive in width with the lower end of each said gate opening disposed inwardly and radially of the conduit in obstructing relation across said channel.

3. In an exhaust gas conditioner having a housing adapted to contain water and an intersticed charge of diffusing material transversely of the housing above the water therein, a conduit upstanding interiorly of the

housing through said charge, a closed lower end on said conduit submerged in the housing-confined water, an open upper end on said conduit above said charge, an exhaust gas input line coaxial with and interiorly of said conduit defining an annular channel between its outer wall and the inner wall of the conduit, the lower end of said line being spaced above the closed lower end of the conduit to discharge its flow for uprise through said annular channel, gate openings intersecting the conduit upwardly adjacent the lower end of said line for the admission of water to said channel, and a tongue radially and inwardly of the conduit at the lower end of each said gate opening and abutting at its inner end against said line in obstructing relation with the channel.

4. In an exhaust gas conditioner having a housing adapted to contain water and an intersticed charge of diffusing material transversely of the housing above the water therein, a conduit adjustably upstanding interiorly of the housing through said charge, a closed lower end on said conduit submerged in the housing-confined water, an open upper end on said conduit above said charge, an exhaust gas input line coaxial with and interiorly of said conduit defining an annular channel between its outer wall and the inner wall of the conduit, the lower end of said line being adjustably spaced above the closed lower end of the conduit to discharge its flow for uprise through said annular channel, gate openings intersecting the conduit upwardly adjacent the lower end of said line for the admission of water to said channel, means adjustable to vary the effective areas of said gate openings, and a tongue at and coextensive in width with the lower end of each said gate opening disposed inwardly and radially of the conduit and abutting at its inner end against said line in obstructing relation with the channel.

5. In an exhaust gas conditioner having a housing formed with top and bottom members and adapted to contain water and an intersticed charge of diffusing material transversely of the housing between said top and bottom members, a collar fixed to and closing against the inner face of said bottom member in axially-perpendicular relation therewith, a right-cylindrical, tubular conduit threadedly engaged at its lower end in said collar to upstand interiorly of the housing through said charge with its open upper end above the charge, means coaxial with and interiorly of said conduit defining an annular channel between its outer wall and the inner wall of the conduit, the lower end of said means being spaced above the lower end of the conduit, means for the input of exhaust gases through said first means to the lower end of the conduit for uprise through said annular channel, gate openings intersecting the conduit upwardly adjacent the lower end of said annular channel for the admission of water thereto, and a tongue radially and inwardly of the conduit at the lower end of each said gate opening in obstructing relation with said channel.

6. In an exhaust gas conditioner having a housing formed with top and bottom members and adapted to contain water and an intersticed charge of diffusing material transversely of the housing between said top and bottom members, a collar fixed to and closing against the inner face of said bottom member in axially-perpendicular relation therewith, a right-cylindrical, tubular conduit threadedly engaged at its lower end in said collar to upstand interiorly of the housing through said charge with its open upper end above the charge, an exhaust gas input line threadedly mounted through the housing top member and depending coaxially and interiorly of the conduit to define an annular channel between its outer wall and the inner wall of the conduit, the lower end of said line being spaced above the lower end of the conduit to discharge its flow for uprise through said annular channel, gate openings intersecting the conduit upwardly adjacent the lower end of said line for the admission of water to the channel, and a tongue radially and inwardly of the conduit at the lower end of each gate opening and

abutting at its inner end against said line in obstructing relation with the channel.

7. In an exhaust gas conditioner having a housing formed with top and bottom members and adapted to contain water and an intersticed charge of diffusing material transversely of the housing between said top and bottom members, a collar fixed to and closing against the inner face of said bottom member in axially-perpendicular relation therewith, a right-cylindrical, tubular conduit threadedly engaged at its lower end in said collar to upstand interiorly of the housing through said charge with its open upper end above the charge, an exhaust gas input line threadedly mounted through the housing top member and depending coaxially and interiorly of the conduit to define an annular channel between its outer wall and the inner wall of the conduit, the lower end of said line being spaced above the lower end of the conduit to discharge its flow for uprise through said annular channel, ribs instanding radially of the conduit in centering engagement with the lower end of said line, gate openings intersecting the conduit between said ribs and upwardly adjacent the lower end of said line for the admission of water to the channel, means adjustable to vary the effective areas of said gate openings, and a tongue at and coextensive in width with the lower end of each said gate opening disposed inwardly and radially of the conduit and abutting at its inner end against said line in obstructing relation with the channel.

8. In an air lift pump having a tubular conduit upstanding from a closed lower end adapted to be submerged in water, an open upper end on said conduit, a member coaxial with and interiorly of said conduit in spaced relation of its lower end above the conduit closed end, said conduit and member coacting to define an annular channel between the outer wall of the member and the inner wall of the conduit, means for the input of gas through said member to the lower end of the conduit for uprise through said channel, and means for the admission of water to said channel, means promotive of intimate gas and water admixture as an incident of water elevation through said channel, said latter means comprising gate openings constituting the means for the admission of water to the channel intersecting said conduit upwardly adjacent the lower end of said member and a tongue radially and inwardly of the conduit at the lower end of each gate opening and abutting at its inner end against said member in obstructing relation with the channel.

9. In an air lift pump having a tubular conduit upstanding from a closed lower end adapted to be submerged in water, an open upper end on said conduit, a member coaxial with and interiorly of said conduit in spaced relation of its lower end above the conduit closed end, said member and conduit coacting to define an annular channel between the outer wall of the member and the inner wall of the conduit, means for the input of gas through said member to the lower end of the conduit for uprise through said channel, and means for the admission of water to said channel, means promotive of intimate gas and water admixture as an incident of water elevation through said channel, said latter means comprising gate openings constituting the means for the admission of water to the channel intersecting said conduit upwardly adjacent the lower end of said member and a tongue radially and inwardly of the conduit at the lower end of each gate opening and abutting at its inner end against said member in obstructing relation with the channel; together with means adjustable to vary the effective areas of said gate openings.

10. In an air lift pump having a tubular conduit upstanding from a closed lower end adapted to be submerged in water, an open upper end on said conduit, a gas input line coaxially with and interiorly of said conduit with its delivery end spaced above the conduit closed end, said line and conduit coacting to define an annular channel between the outer wall of said line and the inner

wall of the conduit for the uprise of the delivered gases, and means for the admission of water to said channel, means promotive of intimate gas and water admixture as an incident of water elevation through said channel, said latter means comprising gate openings constituting the means for the admission of water to the channel intersecting said conduit upwardly adjacent the delivery end of said line and a tongue at and coextensive in width with the lower end of each said gate opening disposed inwardly and radially of the conduit and abutting at its inner end against said line in obstructing relation with the channel.

11. In an air lift pump having a tubular conduit upstanding from a closed lower end adapted to be submerged in water, an open upper end on said conduit, a gas input line coaxial with and interiorly of said conduit with its delivery end spaced above the conduit closed end, said line and conduit coaxing to define an annular channel between the outer wall of said line and the inner wall of the conduit for the uprise of the delivered gases, and means for the admission of water to said channel, means 20

5
